(57) **CLAIM**

The ornamental design for a display mount with single articulating arm, as shown and described.

DESCRIPTION

FIG. 1 is a front perspective view of a display mount with single articulating arm according to the invention;

FIG. 2 is a front elevation view of the display mount with single articulating arm depicted in FIG. 1;

FIG. 3 is a side elevation view of the display mount with single articulating arm depicted in FIG. 1;

FIG. 4 is an opposing side elevation view of the display mount with single articulating arm depicted in FIG. 1;

FIG. 5 is a top plan view of the display mount with single articulating arm depicted in FIG. 1; and,

FIG. 6 is a bottom plan view of the display mount with single articulating arm depicted in FIG. 1.

The portions of the display mount with single articulating arm shown in broken lines form no part of the claimed design.

The rear elevation of the depicted mounts is not claimed, and hence is not depicted.
